(57) **CLAIM**

The ornamental design for container with pump, as shown and described.

DESCRIPTION

FIG. 1 is a perspective view of a container with pump showing our new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom plan view thereof.

The broken lines in the drawings showing the container with pump illustrate the portions of the container with pump that form no part of the claimed design.
